Rhodom M. Brooks

UNITED STATES PATENT OFFICE

RHODOM M. BROOKS, OF PIKE COUNTY, GEORGIA.

IMPROVEMENT IN PORTABLE REVOLVING SCREW-PRESSES.

Specification forming part of Letters Patent No. 59,352, dated November 6, 1866.

To all whom it may concern:

Be it known that I, RHODOM M. BROOKS, of the county of Pike, and in the State of Georgia, have invented a new and useful Improvement in Portable Revolving Screw-Presses; and do hereby declare that the following is a full, clear, and exact description thereof, reference being had to the accompanying drawings, and to the letters of reference marked thereon.

In the annexed drawings, making part of this specification, A A represent two uprights, which are mortised into two sills, B B, at their bottoms, and also into a cross-piece, E, which runs across from one sill to the other.

C C are braces, which stand upon each side of the uprights A A, being mortised at their lower ends into the sills B B. The upper ends of these braces are mitered or beveled to rest against the uprights, and are slotted, as shown, in order that a pin, as seen at x x, may be driven through the uprights, and also into the slots in their ends, to confine them in position.

The two upper ends of the uprights A A are provided with mortises, into which pass tenons upon the ends of the cross-bar D. F F are two braces, which rest between the uprights A and the cross-tie D.

The several pieces framed together as thus described form the frame which supports the press-box, which will be hereinafter described.

The frame of the press-box consists of four upright metallic bars, G, (two at each end,) with metallic cross-bars H H at the ends connecting said uprights together; also of two metallic cross bars or ties, M, at top, and a bed or bottom, R. Within this frame the press-box is secured.

S S' represent the upper and lower sections of the sides of the box. Said sides are, of course, provided with suitable and corresponding end pieces. These sides and ends of the box are confined in position within the metallic frame by means of the wooden cross ties or bars J J and I I.

L represents a screw-rod, made either of metal or of wood, (but I prefer metal,) which has secured to its lower end a follower, K. This follower is made so as to fit snugly in the press-box.

N represents a wooden cross-piece at the top of the metallic frame. Through this cross-piece the screw-rod L passes, and then passes into a nut, O. This nut, which is made of metal, is secured at its upper end to a plate,

a, which said plate is permanently secured to the cross-piece D by means of screws or bolts.

P represents a metallic collar, through which the nut O passes. This collar catches under the metallic cross-ties M M. The cross-ties M M are bolted together at a suitable distance apart on each side of this nut to keep them from spreading when pressure is put on them.

The screw-rod L passes through the bar D, as shown.

W represents a pivot at the center of the bed or bottom R, which said pivot rests in a suitable socket in the lower cross-tie, E, of the outer frame.

The press-box is intended to revolve, while pressing cotton, upon the screw-rod L as a pivot at its upper end, and the pivot W at its lower end.

T represents a lever, secured by proper staples to the press-box near its lower end, to which power is attached for revolving said box.

In using this press, the cotton is first placed in the press-box; then the follower K is inserted in the top of the box, and power being applied to the lever T, the box is made to revolve around and around, and as it revolves the nut O, which is held stationary, forces the screw-rod with its follower K down, thus pressing the cotton into bale in the lower section of the press-box.

The sides of the lower section of the box can be taken out and the bale removed after being pressed.

This press may be used for pressing hay, cotton, wool, or any other material, and can be readily taken to pieces and removed to any portion of the field where needed.

Having thus fully described my invention, what I claim as new, and desire to secure by Letters Patent, is—

The combination of the revolving press-box with the outer frame, which supports said box, for the purpose of making a portable press, the several parts being constructed substantially as and for the purpose herein specified.

In testimony that I claim the foregoing I have hereunto set my hand this 11th day of October, 1866.

R. M. BROOKS.
